US00D606838S

(12) **United States Design Patent**
van Deursen

(10) **Patent No.:** **US D606,838 S**
(45) **Date of Patent:** **** Dec. 29, 2009**

(54) **AUTO FEED UTILITY KNIFE**

(75) Inventor: **Gary E. van Deursen**, Essex, CT (US)

(73) Assignee: **American Safety Razor**, Verona, VA
(US)

(**) Term: **14 Years**

(21) Appl. No.: **29/330,653**

(22) Filed: **Jan. 12, 2009**

(51) **LOC (9) Cl. 08-03**

(52) **U.S. Cl. D8/99**

(58) **Field of Classification Search** D8/98,
D8/99, 107; 30/161, 162, 320, 329, 337

See application file for complete search history.

(57) **CLAIM**

The ornamental design for the auto feed utility knife, as shown and described.

DESCRIPTION

FIG. 1 is a front perspective view of the auto feed utility knife, showing the new design;

FIG. 2 is a front view of the auto feed utility knife;

FIG. 3 is a rear view of the auto feed utility knife;

FIG. 4 is a side view of the auto feed utility knife;

FIG. 5 is another side view of the auto feed utility knife;

FIG. 6 is a top view of the auto feed utility knife; and,

FIG. 7 is a bottom view of the auto feed utility knife.

The broken lines showing various elements of the auto feed utility knife are included for the purpose of illustrating non-claimed subject matter and forms no part of the claimed design.

1 Claim, 5 Drawing Sheets
